UNITED STATES PATENT OFFICE.

ALBERT STUFFLEBEAM, OF PARIS, ARKANSAS.

SHAFT-COUPING.

1,251,836.

Specification of Letters Patent.

Patented Jan. 1, 1918.

Application filed May 2, 1914. Serial No. 836,016.

To all whom it may concern:

Be it known that I, ALBERT STUFFLEBEAM, citizen of the United States, residing at Paris, in the county of Logan and State of Arkansas, have invented certain new and useful Improvements in Shaft-Couplings, of which the following is a specification.

This invention relates to churning, and more particularly to that class that are provided with two dashers capable of rotation in opposite directions.

The object of this invention is to provide an improved means for a churn of the kind above described for rotating the dashers of the same at a great speed with the minimum amount of power.

Another object of this invention is the production of a churn having dashers capable of rotation in opposite directions and means intermediate the dashers and operating means for the same, to facilitate the disconnection of the dashers and the operating means.

A still further object of this invention is to provide an improved operating shaft for the dashers that will accomplish the purposes set forth above.

A still further object of this invention is the production of a device of the kind above described that is simple in construction, efficient in operation and consists of the minimum number of parts.

With these and other objects in view, this invention consists of certain novel constructions, combinations and arrangement of parts as will be hereinafter fully described and claimed.

In the accompanying drawings:

Figure 1 is a view in elevation of the improved churn with a portion of the milk or cream receptacle broken away to show the dashers positioned within the same.

Fig. 2 is a view in elevation of the improved operating shaft used with this invention with a part of the same shown in vertical section.

Fig. 3 is a section taken on the line 3—3 of Fig. 1.

Referring to the parts by reference numerals, 10 denotes the base of the churn having an upwardly extending standard 11 at one end thereof and webs 12 formed integrally with said base and said standard to provide a substantial structure. At the opposite end of the standard 11 from that of the formation of the webs 12 are spaced

arms 13 having enlarged bearings 14 at the ends of the same. These spaced arms 13 are positioned at substantially right angles to the standard 11. Connecting these spaced arms 13 is a vertically extending connecting arm 15, having an enlarged bearing 16 formed intermediate its length. Formed in the standard 11 in alignment with the enlarged bearing 16 is a bearing 17, and a bearing 18 is also formed in the standard 11 in alignment with the lower of the spaced arms 13.

Mounted for rotation within the milk or cream receptacle 19 is a shaft 20, having the dasher 21 secured to the same by means of the set screw 22 passing through the hub of the dasher and engaging the said shaft. This shaft 20 is made of two portions, an upper and a lower one, the lower one having an enlarged head 23 at the upper end thereof provided with a socket 24, said socket being square in cross section. The upper part of the shaft 20 comprises an elongated enlarged portion 25 adjacent the upper end thereof, and at the lower end of the same is a projection 26 that is square in cross section and adapted for placement in the socket 24 formed in the enlarged head 23 of the lower portion of the shaft 20.

A sleeve 27 is also mounted for rotation in the receptacle 19, and is mounted on the lower end thereof a dasher 28 secured to the same by means of the set screw 29. This sleeve 27, as will be seen, is positioned over the lower portion of the shaft 20, and the upper end of the sleeve abuts against the shoulder formed on the shaft 20 by means of the enlarged head 23, and positioned upon the upper portion of the shaft 20 between the substantially elongated enlarged portion 25 and the upper edge of the enlarged head 23 of the lower portion of the shaft 20 is a sleeve 30. Said sleeve 30 and sleeve 27 are connected by means of the collar 31 having the reduced ends 32 through which the set screws 33 pass to engage the sleeves 30 and 27 and thereby securing them rigidly together.

Mounted on the sleeve 30 and spaced from the upper edge of the collar 31 by means of the washer 34, is a beveled gear 35. A beveled gear 36 is also keyed to the upper end of the shaft 20. A third beveled gear 37 is carried by the shaft 38 and meshes with the two gears 35 and 36, and on the opposite end of the shaft 38 from that of the gear 37 is a

pinion 39 that meshes with a gear 40 that is secured to a stub shaft 41 that is positioned in the bearing 18 and secured thereto by a cotter pin 42. A handle 43 is secured to one end of the stub shaft 41, and by rotating the same gives movement to the gear 40 thence to the pinion 39 and by means of the beveled gears 35, 36 and 37 to the shaft 20 and the sleeves 27 and 30 which, of course, having 10 the dashers keyed thereto, rotate the same.

It will be seen that a device has been constructed that will accomplish the objects as set forth. The collar 31 and the set screws 33 in combination with the sleeves 27 and 30 15 and the shaft 20 afford a detaching means, whereby the dashers 21 and 28 can be easily detached from the operating means and the receptacle 19 can be moved to a desired position and the dashers withdrawn from the 20 same.

It will also be seen that the operating means for the same is a very substantial structure, inasmuch as there is provided enlarged bearings 16, 17 and 18 for the shaft 38 and stub 25 shaft 41. The enlarged bearings 14 at the end of the spaced arms 13 afford a substantial supporting means for the sleeve 30 and the shaft 20.

What is claimed is:—

30 1. In a shaft coupling, a shaft having an upper and lower portion, said lower portion provided with an enlarged head at the upper end thereof having a socket formed therein, the upper portion of said shaft having a

projection positioned in said socket, a sleeve 35 mounted upon the lower portion of said shaft, a second sleeve positioned upon the upper portion of said shaft, and having its lower edge in abutment with the upper face of said lower portion of the shaft, a collar 40 having openings formed adjacent the upper and lower ends thereof, and set screws in said openings having the ends thereof positioned against said sleeves for rigidly securing the same as and for the purpose set 45 forth.

2. In a shaft coupling, a shaft having an enlarged head at one end thereof forming a shoulder, a second shaft engaging the enlarged head of said first mentioned shaft, a 50 sleeve on said first mentioned shaft, a second sleeve on said second shaft, the upper end of said first mentioned sleeve being in engagement with the shoulder formed by said enlarged head of said first mentioned shaft, means engaging said sleeves whereby said first mentioned shaft and said sleeves are held together, said shafts being supported by means of said first mentioned sleeve in engagement with said shoulder on said first 60 mentioned shaft as and for the purpose set forth.

In testimony whereof I affix my signature in presence of two witnesses.

ALBERT STUFFLEBEAM.
